CLAIM

The ornamental design for a scraper for a barbecue, as shown and described.

DESCRIPTION

FIG. 1 is a perspective view of a scraper for a barbecue showing my new design;

FIG. 2 is a bottom plan view, the top plan view being the mirror image thereof;

FIG. 3 is a right side elevational view thereof;

FIG. 4 is a left side elevational view thereof; and,

FIG. 5 is a front elevational view thereof.

The broken lines shown in FIGS. 1, 2, 3, and 4 are for illustrative purposes only and form no part of the claimed design.
